UNITED STATES PATENT OFFICE.

WILLIAM J. TAYLOR, OF NEW ALBANY, INDIANA.

POUCH OR SACK HOLDER.

SPECIFICATION forming part of Letters Patent No. 242,395, dated May 31, 1881.

Application filed August 21, 1880. (No model.)

To all whom it may concern:

Be it known that I, WILLIAM J. TAYLOR, of New Albany, in the county of Floyd and State of Indiana, have invented a new and Improved 5 Pouch and Sack Holder, of which the following is a specification.

The object of this invention is to provide a convenient device for holding mail pouches or sacks in an open position.

10 Figure 1 is a partly-sectional side elevation of the device. Fig. 2 is a plan of the same. Fig. 3 is a sectional elevation of a portion of the ring or holder, showing the manner in which the hooks are attached thereto.

15 Similar letters of reference indicate corresponding parts.

In the drawings, A represents the ring or holder, consisting of an outer band, a, and an inner band, b, which latter is attached to the 20 inside of the band a at several points, as shown at c, and sprung away therefrom at the intermediate points, thereby forming the vertical openings, as shown at d, for the reception and sliding adjustment of the hooks B B, that are

25 suspended on the edge of the said band b, with their bends beneath the lower edge of the band a and their points projecting upward on the outside of said ring or holder A.

For convenience, the ring or holder A is 30 hinged, as shown at f, to a plate, C, that is designed to be secured in a vertical position to a wall, side of a car, or other upright object.

To the upper part of the plate C is hinged the hook D, that hangs down and engages its 35 point under the lower edge of the holder or ring A, and holds said ring A up in a horizontal position, as shown in Fig. 1, ready for the attachment of pouch or sack.

When the holder or ring A is not in use the 40 hook D is disengaged therefrom, and said ring or holder A is permitted to fall in a vertical position, as indicated in dotted lines at E, Fig. 1, whereby said holder A is put out of the way and made to occupy but little space.

45 The hooks B B may be moved along in the

openings d to be accommodated to the eyelets of pouches or sacks of varying dimensions, having an advantage in this respect over the stationary hooks commonly used for this purpose.

This device occupies no more space when 50 in use than does the pouch or sack when filled, and space can be greatly economized by dropping the ring or holder A into a vertical position when not in use, in which respect this device possesses a decided advantage over the 55 stationary racks now in use for hanging mail-sacks, as the same space is always occupied by the stationary rack, whether it be in use or not.

I do not strictly confine myself to the shape herein shown of the ring or holder A, as for 60 some positions or localities a holder with straight sides and front and rounded corners, or a holder of other suitable outline, may be advantageously used; nor do I confine myself to the sliding hooks B B for the suspension of 65 the pouch or sack, as I propose to make said hooks stationary and sharp-pointed for holding sacks and pouches that are not provided with eyelets.

While stationary hooks would answer in the 70 place of slide-hooks for ordinary sacks, they are not practicable with mail-pouches, which must not be pierced by the hooks. Again, when a stationary hook is run through an eyelet in the pouch, it will be the merest accident 75 if another stationary hook will meet another eyelet, the distances between the pouch-eyelets never being uniform.

Having thus fully described my invention, I 80 claim as new and desire to secure by Letters Patent—

A mail-pouch holder consisting of the ring A, sliding hooks B, and hook-plate DC, whereby the bag may be fitted to the holder by the simple adjustment of the sliding hooks to fit 85 the eyelets, as described.

WILLIAM JAMES TAYLOR.
